UNITED STATES PATENT OFFICE.

RUDOLF LOEB, OF JENKINTOWN, PENNSYLVANIA.

PROCESS OF MAKING EMBROIDERY ORNAMENTATION.

1,233,259.

Specification of Letters Patent. Patented July 10, 1917.

Original application filed June 29, 1914, Serial No. 848,023. Divided and this application filed December 19, 1914. Serial No. 878,096.

To all whom it may concern:

Be it known that I, RUDOLF LOEB, a citizen of the United States, and a resident of Jenkintown, Montgomery county, Pennsylvania, have invented an Improved Process 5 of Making Embroidery Ornamentation, (being a division of my application for patent filed June 29, 1914, Serial No. 848,023,) of which the following is a specification.

10 My invention relates to ornamentation effected by embroidery stitching, and comprises the method or process of forming an ornamental figure made of a plurality of needle threads which are disposed radially 15 and superposed upon each other to form a raised knot or button-like ornamentation which may be, relatively speaking, of any size desired.

In carrying out the method or process of 20 producing the raised knot or button-like ornamentation constituting the subject of my invention, I make use of a machine employing two oscillating needles vibrating in a fixed path in line with their position. By 25 rotating the goods upon which the stitches are laid with respect to a predetermined center disposed at some point intermediate the extreme throw of the respective needles, the stitches laid by these threads are caused 30 to cross each other and produce a raised knot, the height of which may be easily regulated by the operator; the machine being stopped when the stitching has been effected to the desired height. The diameter 35 of the knot is regulated by the throw or oscillation of the needles, and their movement may be effected and controlled in the manner set forth in my Patent No. 1,193,803 dated August 8, 1916.

40 My present invention comprises the process of making my improved embroidery ornamentation, the embroidery as an article of manufacture being claimed in application Serial No. 848,023 before referred to, 45 of which this application is a division.

These and other features of my invention will be more fully described hereinafter, reference being had to the accompanying drawings, in which:

50 Figure 1, is an enlarged plan view of a piece of fabric, showing the obverse side of the ornamental embroidery knot made in ac-

cordance with my invention; showing also the position of the needles, a presser foot and means for turning the fabric:

55

Fig. 2, is a plan view showing the reverse side of the embroidery ornamentation illustrated in Fig. 1;

Fig. 3, is a sectional view illustrating the manner in which the needles operate in the fabric to lay the stitches thereon, and

Figs. 4, 5 and 6, are enlarged sectional views showing various steps in the formation of the ornamental knot.

In the production of the ornamental embroidery forming the subject of my present invention, I employ a sewing machine with a pair of vibrating needles, such as shown at 1 and 2, which needles are set in line with each other and vibrate in a single plane coincident with the plane of their position. The machine in which these needles are mounted is equipped with mechanism that will enable the operator to turn the work with respect to a predetermined center while 75 the needles are vibrating and laying the desired stitches; the movement of the fabric with respect to the vibrating needles being wholly under the control of the operator.

With the fabric so controlled, the stitches from the needles will be laid in a radial direction with respect to the predetermined center, and this center will be at some point intermediate the limits of the throw or vibration of the needles. By this means, I 80 am able to produce a novel form of embroidery which consists of a plurality of sets of raised stitches 3 and 4, disposed upon the fabric 5, which stitches cross each other as the fabric is rotated and result in the 85 formation of a raised knot or button-like figure. The stitches 3 and 4 are less in length than the diameter of the ornamentation produced by the same, and by reason of the fact that portions of said stitches 90 cross the predetermined center, a greater bulk of thread will be left there and the height of such center will naturally be 95 raised.

All of the stitches showing on the face 100 of the fabric have loops 6 on the under side of the same, and these loops are caught by a single shuttle thread 7.

The effect of this ornamentation is ma-

terially heightened by the employment of threads of different color, and the size of the knots is controlled by the throw of the needles.

- 5 The fabric may be moved by means of a rotatable member such as shown, for instance, in my application for patent filed Dec. 31, 1913, Serial No. 809,798, or any other rotating means that will turn with 10 the fabric when the operator moves the tambour frame in which the fabric is stretched; such rotating means being preferably supported by a fixed carrier 10. This fabric moving device is adjustable so as to change 15 the center of the same with respect to the throw of the needles and effect circular ornamentation of various sizes. The needles may also be set in different relations with respect to each other; changes in the throw 20 of the shuttle being correspondingly effected.

In order to accommodate the raised center made by the stitches 3 and 4 during the formation of the same, the presser foot 12 is 25 provided with an enlarged space 13 at the outer end of the slotted portion accommodating the needles. This presser foot is employed solely to hold the fabric while the needles are in the same to insure proper 30 coaction of the shuttle thread and is raised when the needles are raised; having no feeding or other moving effect upon the fabric which is wholly under the control of the operator.

35 In the preferred process of producing the ornamental embroidery forming the subject of my invention, the raised knot or circular ornament is formed of continuous stitches from two independent threads laid 40 by a pair of vibrating needles upon the rotating fabric, which needles oscillate or vibrate in a plane coincident with the plane of their setting, so that in the formation of such knot or ornament stitches will be laid 45 simultaneously from opposite sides of the

same, and the completion of the ornamentation is very rapid.

I claim:

1. The process of producing circular embroidery ornamentation, which consists in 50 disposing upon a piece of material a plurality of annular rows or sets of radial stitches formed by continuous independent threads laid by a plurality of oscillating thread-carrying implements, simultaneously 55 rotating the fabric on an axis that is crossed by the path of the thread-laying implements whereby the stitches that are laid upon the fabric will partially overlap stitches diametrically opposite therefrom substantially 60 at the center of the embroidery ornamentation and form a relatively rounded cone-shaped mass projecting above the surface of the fabric.

2. The process of producing circular embroidery ornamentation, which consists in 65 disposing upon a piece of material a plurality of annular rows or sets of radial stitches formed by continuous independent upper threads laid by oscillating thread-carrying means, simultaneously rotating the fabric on an axis that is crossed by the path 70 of the thread-laying means whereby the stitches that are laid upon the fabric will partially overlap stitches diametrically opposite therefrom substantially 75 at the center of the embroidery ornamentation and form a relatively rounded cone-shaped mass projecting above the surface of the fabric, and inserting a single locking thread through the 80 loops of the upper threads, which extend on the under side of the fabric.

In testimony whereof, I have signed my name to this specification, in the presence of two subscribing witnesses.

RUDOLF LOEB
